(57) **CLAIM**

The ornamental design for a bottle, as shown and described.

DESCRIPTION

FIG. 1 is a perspective view of a bottle embodying the new design;

FIG. 2 is a side elevational view of FIG. 1, wherein all sides comprise a mirror image thereof;

FIG. 3 is a top plan view of FIG. 1; and,

FIG. 4 is a bottom plan view of FIG. 1.

Elements shown in broken lines do not constitute part of the claimed design.
